Primary Examiner — Clare E Heflin(74) *Attorney, Agent, or Firm* — Gottlieb, Rackman & Reisman, P.C.(57) **CLAIM**

The ornamental design for a light fixture, as shown and described.

DESCRIPTION

FIG. 1 is a perspective view of the light fixture showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The break lines in FIGS. 1-5 are to indicate that the appearance of any portion of the light fixture between the break lines form no part of the claimed design, and the broken lines shown in the drawings are included for the purpose of illustrating portions of the article that form no part of the claimed design as well.

1 Claim, 5 Drawing Sheets(56)
